UNITED STATES PATENT OFFICE.

JOHN B. BAILY, OF CEDAR RAPIDS, IOWA.

ICE-SHAVER.

SPECIFICATION forming part of Letters Patent No. 596,566, dated January 4, 1898.

Application filed June 10, 1897. Serial No. 640,186. (No model.)

To all whom it may concern:

Be it known that I, JOHN B. BAILY, a subject of the Queen of Great Britain, residing at Cedar Rapids, in the county of Linn and State of Iowa, have invented certain new and useful Improvements in Ice-Shaves; and I do declare the following to be a full, clear, and exact description of the invention, such as will enable others skilled in the art to which it appertains to make and use the same.

This invention relates to ice-shaves; and it has for its prime object to provide an implement for such purposes which may be used with ease and facility and which will leave the shaved ice free from the bowl or holder when the base or bottom has been removed, so that such ice can be quickly turned into a glass or other receptacle.

A further object of the invention is to provide a simple and durable construction which will require no experience to operate and one in which the parts are not liable to get out of order.

Other objects and advantages will appear from the following description and claims when taken in connection with the annexed drawings, in which—

Figure 1 is a vertical sectional view taken in the plane indicated by the dotted line ww on Fig. 2. Fig. 2 is a similar view taken in the plane indicated by the dotted line xx on Fig. 1. Fig. 3 is a horizontal sectional view taken at the point indicated by the dotted line yy on Fig. 1. Fig. 4 is a perspective view of the bowl or holder removed. Fig. 5 is a perspective view of the bottom detached, and Fig. 6 is a perspective view of the planer-knife.

Referring by letter to said drawings, A indicates the bottom or base, and B the bowl or holder. The base or bottom, which is of a general circular form in outline, may be composed of stout metal or other suitable material having its face a provided with two transverse slots b , which may be of a suitable length and width, according to the fancy or dictation of the manufacturer, for the upward passage of the shaved ice and the projection of the planer knives or cutters. In the present illustration of my invention I have shown the cutter as composed of a single piece of steel having the obliquely and

oppositely directed cutting edges c and the connecting or central flat portion d with holes e to receive rivets f , screws, or other suitable fastening devices, and the bottom or base may be recessed on its under side in advance of each cutter, as shown at g , so as to facilitate the entrance of the shaved ice. I would have it understood, however, that I do not limit myself to this construction of cutter, as I may form each cutter separately, although I prefer to use the form which I have shown.

Rising from the upper side of the base or bottom is a marginal flange h , which flange is separated diametrically, as shown at i , to form entrances for lugs on the bowl, as will be presently described, and the inner side of each flange h is grooved or recessed from one end to near the other, as shown at l , where they are provided with stops j , the stops on the flanges being at the ends farthest from each other, so that the bowl or holder can be turned to the right only in making the connection and to the left in detaching the bottom therefrom.

The bowl or holder may be of any suitable shape, although I prefer to make it of approximately cone shape, as shown, and I provide the mouth on its outer side and at diametrically opposite points with lugs k , which are designed to enter the separated parts i of the bottom and take into grooves l in the flanges h . By this means it will be seen that when the bowl or holder has been placed upon the base, with the lugs k entering between the separated ends of the flange h , by then giving the bowl a half-turn to the right these lugs will snugly engage the recessed parts of the flange, and consequently hold said bowl to its base or bottom, when the device can be conveniently grasped by one hand and reciprocated on a piece of ice, so that the shavings will pass up through one slot of the bottom when the implement has been moved in one direction and up through the other slot when the implement has been moved in the opposite direction, so that the shaving of the ice will be very rapid and the bowl can be quickly filled with but little exertion. To remove the bowl from the base or bottom, it is simply necessary to reverse the direction of movement of said bowl until the lugs thereon have been brought to the openings i .

An objection heretofore experienced with devices of this character has been that the ice as it packs in the bowl or holder will adhere thereto, so that it has become necessary 5 to either knock the holder after removing the bottom or to employ a spoon or some suitable implement to dig out the shaved ice. To overcome this objection, I have provided a scraper, which is here shown as composed of 10 a U-shaped piece of flat metal C, which may have sufficient resiliency to snugly engage the inner walls of the holder and is pivoted at its center within the bowl or holder and in the top thereof, as shown at m. The ends of 15 this scraper, which is shaped to conform to the interior of the bowl, project a sufficient distance laterally from the mouth to engage the flanges h at the recessed or cut-out portions, so that the scraper will remain stationary with respect to the bottom and will scrape the entire inner surface of the bowl before the bottom can be removed, thereby severing the ice from the bowl in the act of removing the bowl from the bottom.

25 I would have it understood that I do not limit myself to the particular form of scraper which I have shown, nor to any material from which such scraper may be made, as I am aware that changes can be made in the form 30 and construction as well as the manner of attaching the same to the bowl.

Having thus described my invention, what I claim is—

1. An ice-shave, comprising a base or bottom carrying a cutter, and also having a vertical marginal flange recessed at opposite

points, and each separate section grooved and provided with a stop, and a bowl or holder having its mouth provided laterally and at diametrical points with lugs adapted to enter 40 the grooves of the flange, substantially as specified.

2. An ice-shave, comprising a base or bottom carrying a cutter, and a detachable bowl or holder having a scraper adapted to be 45 moved within the bowl by the detachment of the base, substantially as specified.

3. An ice-shave, comprising a base or bottom carrying a cutter and having a marginal flange on its upper side, said flange being 50 separated at opposite points, and each section internally grooved and provided with a stop, and a bowl or holder having lateral lugs to enter said recessed portions and take into 55 grooves, and a scraper carried by the bowl and adapted to engage the recesses or cut-out portions of the flange of the bottom, substantially as specified.

4. An ice-shave having a bowl or holder adapted to be secured to a suitable base and 60 having the scraper pivoted within the bowl, and conforming to the interior thereof, and adapted to be moved by the movement of the base in the act of detaching the same, substantially as specified.

In testimony whereof I affix my signature in presence of two witnesses.

JOHN B. BAILY.
